(57) **CLAIM**

The ornamental design for a navicular bone plate, as shown and described.

DESCRIPTION

FIG. 1 is a front perspective view of the navicular bone plate comprising the new design;

FIG. 2 is a front elevational view of the design of FIG. 1;

FIG. 3 is a back elevational view of the design of FIG. 1;

FIG. 4 is a top view of the design of FIG. 1;

FIG. 5 is a bottom view of the design of FIG. 1;

FIG. 6 is a left side elevational view of the design of FIG. 1; and,

FIG. 7 is a right side elevational view of the design of FIG. 1.

The relatively light uneven broken lines represent contour, not surface decoration.
